UNITED STATES PATENT OFFICE.

MORRIS FRANK, OF NEW YORK, N. Y.

DESIGN FOR EMBOSSED TEXTILE FABRIC.

41,071.

Specification for Design.

Patented Jan. 3, 1911.

Application filed October 10, 1910. Serial No. 586,406. Term of patent 3½ years.

To all whom it may concern:

Be it known that I, MORRIS FRANK, a citizen of the United States, and residing at New York, in the county of New York and State of New York, have invented a certain new, original, and ornamental Design for an Embossed Textile Fabric, of which the following is a specification, reference being had to the accompanying drawing, forming part thereof.

The figure is a plan view of a portion of an embossed textile fabric showing my new design.

I claim:—

The ornamental design for an embossed textile fabric as shown.

MORRIS FRANK.
